UNITED STATES PATENT OFFICE.

EMILE BORNAND, OF STE. CROIX, SWITZERLAND.

MUSIC-BOX.

SPECIFICATION forming part of Letters Patent No. 391,504, dated October 23, 1888.

Application filed February 4, 1888. Serial No. 263,018. (No model.)

To all whom it may concern:

Be it known that I, EMILE BORNAND, of Ste. Croix, Switzerland, have invented certain new and useful Improvements in Music-Boxes, 5 of which the following is a full, clear, and exact description.

The invention relates to music-boxes with interchangeable cylinders; and the object of the invention is to provide certain new and useful improvements in music-boxes by which the cylinders can be easily and accurately placed in position in the box and quickly interchanged whenever desired.

The invention consists of a mainspring-case 15 provided with a gear-wheel meshing into the pinion of the wind-wheel, and also provided with a second gear-wheel meshing into a pinion on the cylinder-shaft.

The invention also consists of certain parts 20 and details and combinations of the same, as will be fully described hereinafter, and then pointed out in the claims.

Reference is to be had to the accompanying drawings, forming a part of this specification, 25 in which similar letters of reference indicate corresponding parts in all the figures.

Figure 1 is a plan view of a music-box provided with my improvement. Fig. 2 is a longitudinal sectional elevation of the same on the line $x-x$ of Fig. 1. Fig. 3 is a vertical cross-section of the same on the line $y-y$ of Fig. 1, and Fig. 4 is a like view of the same on the line $z-z$ of Fig. 1.

The music-box A is provided with the usual 35 comb, B, on which operates in the usual manner the cylinder C, of any approved construction, and carrying on its shaft D the pinion E, meshing into the gear-wheel F, formed on the mainspring-case F' of the driving mechanism G, of any approved construction, and serving 40 to impart the usual rotary motion to the said shaft D and its cylinder C, which is mounted to slide on and to rotate with the shaft D. On the mainspring-case F' is also formed a second 45 gear-wheel, F², meshing into a pinion, F³, connected in the usual manner with the wind-wheel or regulator F⁴, of any approved construction.

The cylinder-shaft D, as well as the wind-wheel F⁴, are thus operated on simultaneously 50 by the rotation of the mainspring-case F' of the driving mechanism G, and when the said

spring-case F' and wind-wheel F⁴ are stopped or started in the usual manner by the ordinary stop-lever, F⁵, then the cylinder-shaft D and its cylinder C are also stopped or started. The gear-wheel F and the pinion E have such a relative number of teeth that one revolution of the mainspring-case F' causes three revolutions of the cylinder C.

The shaft D is provided with two round bearing parts, H and I, one near each of its ends, and the flattened parts J and K, of which the part J is extended by a lug, L, as shown. The shaft D is held to rotate with its round bearing parts H and I in the bearings N and O, respectively, which are secured in the usual manner to the main frame, and each of which is provided with an inclined slot, P, leading to a round bottom slot, P', in which the round bearing parts H and I of the shaft D rotate. On the bearing N is also formed a circular recess, P², concentric with the round bottom slot, P', and into the said circular recess P² projects the inner end of the lug L, to prevent this end 70 of the shaft D from wabbling.

On the shaft D, next to the flattened part K, is formed a collar, Q, on the inside of the bearing O, and on this collar Q operate, between it and the bearing O, the wedge-shaped 80 prongs R R, secured to the arm S, pivoted at S' on the bearing O, and provided at its front end with a handle, S², for conveniently operating the said arm. When the arm S is pressed down, the prongs R R straddle the shaft D at 85 the flattened part K, so that the shaft is prevented from moving upward. On the pivoted end of the arm S is formed a wedge-shaped lug, S³, adapted to operate on a lug, T', formed on the repeating or changing lever T, so that 90 the latter is thrown out of contact with the usual repeating and changing mechanism located on the cylinder C whenever the said arm S is moved backward in order to change the cylinder and its shaft.

On the ends of the shaft D are formed the knobs or buttons U and U', respectively, serving to handle the shaft conveniently in moving it, with the cylinder C, to and from the bearings N and O. On the button U presses 100 a spring, V, serving to move the shaft D longitudinally in its bearings N and O in the direction of the arrow a'. The slots P are somewhat narrower than the diameters of the bot-

tom slots, P', so that when the round parts H and I are engaged in the said bottom slots, P', the cylinder cannot be lifted out of the bearings N and O.

5 The operation is as follows: The lug L on the shaft D is placed in such a position in relation to the cylinder C that when the latter stands at rest at the end or beginning of a piece of music with the comb the said lug L and flattened parts J and K of the shaft D are in line with the inclined slots P in both bearings N and O. When the driving mechanism G is at rest, the several parts are in the position shown in the drawings, and when the 15 operator now desires to change the shaft D and its cylinder C for one of like construction, with the exception of different pieces of music being on the cylinder, he throws the arm S backward, so that the prongs R disengage the shaft D and the collar Q, and at the same time the lug S' presses the pin T' backward, whereby the lever T is thrown out of contact with the changing and repeating mechanisms on the cylinder C. The spring V pressing on the shaft D causes the latter to slide 25 longitudinally in the direction of the arrow a', so that the pinion E is disengaged from the gear-wheel F of the driving mechanism G, and the round bearing parts H and I of the shaft 30 D are disengaged from the round bottom slots, P', of the bearings N and O, and the flattened parts J and K now enter the said bottom slots, P', the lug L entering the inclined slot P of the bearing N. The operator now takes hold 35 of the knobs U and U' and lifts the shaft D upward and out of the bearings N and O through the inclined slots P. A shaft of like construction and provided with a cylinder having different pieces of music on its rim can 40 now be inserted by placing the flattened parts J and K in the inclined slots P, with the lug L on top. When the shaft rests in the bottom slots, P', the operator moves the arm S forward and downward, so that the wedge-shaped 45 prongs R straddle the shaft D, and at the same time the wedge-shaped parts of the prongs press against the face of the collar Q, whereby the latter, with the shaft D and the cylinder C, is moved longitudinally in the inverse direction of the arrow a' until the flattened parts 50 J and K of the shaft D have left the bottom slots, P', and the round bearing parts H and I have entered the said bottom slots, P', of the bearings N and O. The spring V is thus compressed, and remains so until the arm S is again moved out of contact with the collar Q, as above described. The pinion E is moved 55 into mesh with the gear-wheel F of the driving mechanism G when the shaft D is moved 60 in the inverse direction of the arrow a', as above described.

Thus it will be seen that the driving mechanism, the comb, and the changing and repeating devices are not at all disturbed while the 65 changing of the cylinder takes place. The whole arrangement is extremely simple and durable in construction, and the cylinder al-

ways stands at rest at the beginning or the end of the piece of music with the comb B, so that the operator does not injure any of the parts 70 while changing the cylinders.

Having thus fully described my invention, I claim as new and desire to secure by Letters Patent—

1. In a music-box, a mainspring-case provided with two gear-wheels, of which one operates the cylinder and the other the wind-wheel, substantially as shown and described. 75

2. In a music-box, the combination, with a mainspring-case provided with a second gear-wheel, of a wind-wheel operated by the said second gear-wheel, substantially as shown and described. 80

3. In a music-box, the combination, with a mainspring-case provided with two gear-wheels, of a cylinder operated by one of the said gear-wheels and a wind-wheel operated by the other gear-wheel, substantially as shown and described. 85

4. In a music-box, the combination, with the comb, the driving mechanism, and the changing and repeating devices, of a cylinder held at rest on the said comb, a shaft carrying the said cylinder and prevented from rotating in its bearings when the cylinder is in the said relative position with the comb, and a pivoted arm for moving the said shaft longitudinally, so that it can revolve in its bearings and is connected with the driving mechanism, said pivoted arm being also adapted to throw the changing and repeating lever out of contact with the cylinder, substantially as shown and described. 90

5. In a music-box, the combination, with slotted bearings, of a shaft having flattened parts adapted to pass into the slots of the said bearings and an arm for moving the said shaft longitudinally, so that the flattened parts are disengaged from the said bearings, substantially as shown and described. 95

6. In a music-box, the combination, with slotted bearings, of a shaft carrying the cylinder and provided with flattened parts adapted to pass into the slots of the said bearings, a collar fastened on the said shaft, and a pivoted arm provided with wedge-shaped prongs adapted to engage the said collar and to straddle the said shaft, so that the latter is moved longitudinally in the said bearings, substantially as shown and described. 100

7. In a music-box, the combination, with slotted bearings, of a shaft carrying the cylinder and provided with flattened parts adapted to pass into the slots of the said bearings, a collar fastened on the said shaft, a pivoted arm provided with wedge-shaped prongs adapted to engage the said collar and to straddle the said shaft, so that the latter is moved longitudinally in the said bearings, and a spring pressing against one end of the said shaft, substantially as shown and described. 115

8. In a music-box, the combination, with the driving mechanism provided with two gear-wheels, of a shaft carrying a pinion mesh-

ing into one of the said gear-wheels, said shaft also carrying a cylinder, slotted bearings supporting the said shaft, a collar fastened on the said shaft, and an arm provided with wedge-shaped prongs engaging the face of the said collar, so as to cause the said shaft to slide longitudinally in its bearings, and to move said pinion into mesh with one of the said gear-wheels, substantially as shown and described.

5 9. In a music-box, the combination, with the changing and repeating lever operating on

the changing and repeating device of the cylinder, of a shaft carrying the said cylinder and mounted in slotted bearings, an arm pivoted on one of the said bearings, and provided with a lug adapted to engage a lug on the said changing and repeating lever, substantially as shown and described. 15
